(57) **CLAIM**

The ornamental design for a faucet cover, as shown and described.

DESCRIPTION

FIG. 1 is a front perspective view of a faucet cover;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the figures are included for the purpose of illustrating portions of the faucet cover that form no part of the claimed design.

1 Claim, 4 Drawing Sheets
